UNITED STATES PATENT OFFICE.

FRANK H. POEPPELMEIER, OF DAYTON, OHIO, ASSIGNOR OF ONE-FOURTH TO LAWRENCE A. POEPPELMEIER, ONE-FOURTH TO VINCENT E. POEPPELMEIER, AND ONE-FOURTH TO JOHN L. WEIGAND, ALL OF DAYTON, OHIO.

TYPE EJECTOR FOR COMPOSING MACHINES.

Application filed April 19, 1927. Serial No. 184,992.

This invention relates to new and useful improvements in type ejectors for type composing machines, and more particularly in the type ejector illustrated and described in my United States Letters Patent No. 1,607,170, granted November 16, 1926.

It is one of the principal objects of my invention to provide for composing machines a type ejector which will automatically accommodate various thicknesses of type without any manual adjustment.

It is another object of my invention to provide automatic means for forcing sticking type down into the path of the ejector.

Other important and incidental objects will be brought out in the following specification and particularly set forth in the subjoined claims.

In the accompanying drawings, Figure 1 is a side view of my type ejector with the cover open, revealing the internal mechanism. In this view the timing pawl is shown moving a type into position in front of the ejector. Figure 2 is a view of the opposite side of the ejector, showing the driving means. Figure 3 is a detail side view of the type ejecting mechanism, showing the type just after it has been ejected, with the control pawl holding the column of type up to give the necessary clearance for the timing pawl to engage the next type to be ejected. Figure 4 is a front view of my type ejector. Figure 5 is a cross-sectional view taken on the line 5-5 of Figure 1, showing the type control lever, timing pawl and controlling pawl. And Figure 6 is a sectional view taken through the lid clamp on the line 6-6 of Figure 1.

Referring to the accompanying drawings for a detailed description of my invention, the numeral 1 designates an ejector housing in which a transverse cam shaft 2 is journaled. Fast on the outer end of the shaft 2 is a sprocket wheel 3. Freely mounted on a shaft 4 above the shaft 2 is an idler sprocket 5 around which the sprocket 3 a sprocket chain 6 passes to rotate the cam shaft 2 from a source of power not shown.

Fast on the inner end of the shaft 2 is a crank disc 7 to which there is pivotally secured by a pin 8 an ejector arm 9 terminating in a notched outer end 10 which enters the bottom portion of a type chute 11 that projects downwardly from a type compos-

ing board 12. (See Figure 1). At its lower end the type chute or throat 11 is open to a printer's chase 13 onto which the type is ejected by the ejector arm 9 in the manner disclosed in my said United States Letters Patent No. 1,607,170.

The type 14 which passes downwardly through the chute 11, is first intercepted by a type control pawl 15 which is pivotally secured by a stud 16 to a type control lever 17 pivotally secured to the casting 1 by a stud 17^a. (See Figure 1). The nose portion 18 of the pawl 15 is held directly in the path of the descending type at the desired times, by a tension spring 19 connected between a shoulder 29 on the pawl 15 and a shoulder 21 on the lever 17. (See Figures 1 and 3).

The lever 17 is of the bell crank type, whose lower part 22 carries a cam roll 23 which is in engagement with a cam surface 24 formed on the periphery of the crank disc 7. The latter is so timed that it will actuate the lever 17 to force the nose 18 of the pawl 15 into the path of the descending type 14 to restrain a further downward movement of the latter until the nose 25 of a timing pawl 26 forces a previous type into the path of the ejector arm 9. Formed on the pawl 26 is a projection 26^a which contacts with the wall of the chute 11 to prevent the nose of the pawl from being pressed too far into the chute by the spring 35 when there is no type in it. The lever 17 is always held in a position to maintain the roll 23 in contact with cam surface 24 on the periphery of the disc 7, by a tension spring 27 connected between a projection 28 on said lever and a pin 29 inserted in a hole in the casting. (See Figure 1).

The nose 18 of the control pawl 15 is forced into the path of the downwardly descending type 14 by the following means. Secured to the casting 1 is a pin 30 which freely projects into a curved slot 31 formed in the lever 17 slightly beyond the stud 17^a, as shown in Figures 1 and 3. This pin 30 is in the path of the downward movement of the tail 32 of the pawl 15, whereby, when the lever 17 raises the said pawl, the nose 18 of the latter will be moved into the chute 11 to intercept the downward movement of the type; and when the lever 17 lowers the pawl 15, the tail 32 of the latter will engage the pin 30, which will cause a movement of

the pawl 15 on the stud 16 to withdraw its nose 18 from the path of the type above it in the chute 11. (See Figures 1 and 3).

The timing pawl 26 is pivotally secured to its upper end by a stud 33 on the extreme outer end 34 of the lever 17. Surrounding the stud 33 is a tension spring 35 which normally maintains the nose 25 of the pawl 26 in the path of the type 14 below the nose 18 of the pawl 15. (See Figure 5). The pawl 26 is formed with a downwardly projecting flange 36 which holds the type 14 straight at all times. (See Figures 1 and 3).

When the outer end 34 of the lever 17 is moved downwardly, the pawl 26 will be forced in the same direction to press a type 14 into the path of outward movement of the ejector arm 9. The outer notched end 10 of the arm 9 is pivotally secured by a pin 37 to a block 38 which is free to slide in a longitudinal groove within an inclined guide 39 secured by screws 40, 40 to a reinforced section 41 of the casting 1. This guide 39 causes the notched end 10 of the ejector arm 9 to have a movement which is substantially defined by a figure 8. Upon its outward movement the notched end 10 of the ejector arm 9 will engage the type forced in its path by the timing pawl 26, to move said type onto the printer's chase 13. (See Figure 3).

Just prior to the ejection of the type, a pinch slide 42 now to be described will be drawn outwardly by a spring 43 to engage its nose 44 to press the type next above the one ejected, against the inner wall of the type chute 11 to hold said type stationary while the nose 25 of the timing pawl 26 is withdrawn from the chute. The withdrawal of the pawl 26 is effected by the engagement of its angular surface 45 with the type as said pawl 26 is raised by the lever 17. (See Figure 3).

The pinch slide 42 is formed with a front slot 46 and a rear slot 47 which receive shouldered studs 48 and 49 respectively on the casting 1. These studs act as guides for a longitudinal movement of the pinch slide 42. The thrust movement of said slide, as before stated, is effected by the tension spring 43, one end of which is connected to a stud 50 on the casting and its other end to a stud 51 on the slide. This stud 51 projects through a clearance hole 52 in the casting 1 to permit it the necessary longitudinal movement. (See Figures 2 and 5).

The rearward movement of the slide 42 is effected by means of a cam disc surface 53 milled on the inner face of the crank disc 7.

Mounted on a stud 54 on the rear end of the slide 42 is a cam roller 55 which is held by the spring 43 in continuous engagement with the cam surface 53 on the inner face of the disc 7. Just before the timing pawl 26 starts its downward movement to

force the type pinched by the slide 42, into the path of the ejector arm 9, said slide will be withdrawn from said type by the cam 53 to release it.

The ejector housing 1 is provided with a cover 56 for enclosing the ejector mechanism just described. In order that this cover may be easily and quickly opened, it is formed with bosses 57, 57 which contain axial holes that register with similar holes in bosses 58, 58 respectively on the casting 1. The bosses 57, 57 are mounted upon their companion bosses 58, 58 in such a manner as to receive hinge pins 59, 59 respectively, to permit said cover a swinging movement. (See Figure 1).

The cover 56 is clamped in a closed position by the following means. Referring to Figures 4 and 6, there is formed in the upper, outer corner of the casting 1 a hole into which is fitted a stud 60. The latter terminates at its inner end in an enlarged portion 61 containing a deep groove 62. The threaded end of the stud 60 is on the outside of the casting to receive a nut 63. (See Figure 6).

Just below the stud 60 the cover 56 is formed with a transverse hole which extends outwardly through a boss 64 on the cover. This transverse hole receives a shaft 65 which is formed on its inner end with a beveled projection 66 which is free to enter the groove 62 in the enlarged end of the stud 60. To the outer end of the shaft 65 a handle 67 is attached whereby the shaft 65 may be turned to lodge the projection 66 tightly in the groove 62 of the stud, to lock the cover 56 to the casting. (See Figures 4 and 6).

In operation, when a selected type 14 descends through the chute 11, it is first intercepted by the nose 18 of the control pawl 15. It will then be raised by the nose of said pawl 15, as shown in Figure 3, to allow sufficient clearance between said type and the type below for the entrance into the chute of the nose 25 of the timing pawl 26. (See Figure 3). Now, when the outer end 34 of the lever 17 descends, it will force downwardly both pawls 15 and 26. The latter pawl will then force the type below into the path of outward movement of the notched end 10 of the ejector arm 9. By this arm, which is actuated by the crank disc 7, the type will be ejected upon the printer's chase 13. To properly guide the type onto the chase, there projects into the lower end of the chute 11 a beveled guide 68 for said type, which is grooved. (See Figure 1).

Before the ejector arm 9 engages the type in front of it, the pinch slide 42 will be moved forward by the spring 43 to engage its nose 44 with the type next above the one to be ejected to hold it in a stationary position against the wall of the chute 11. Then,

the timing pawl 26 will be raised by the lever 17, and during the upward movement of said pawl 26 its angular surface 45 will engage the type held fast in the chute by 5 the pinch slide 42, and by said type be cammed out of the chute. The ejector arm is now free to eject the type in front of it onto the chase 13.

This cycle may be repeated several hundred times a minute to properly eject the 10 selected type from the chute onto the chase without clogging the chute or breaking the type.

I do not wish to be limited to the details 15 of construction and arrangement herein shown and described, and any changes or modifications may be made therein within the scope of the subjoined claims.

Having described my invention, I claim: 20 1. In a device of the type described, the combination with a chute for the descent of type therethrough, of means for laterally ejecting type from the chute, means for entrance into the chute to restrain the downward movement of the type therein, and lever means synchronized with the movement of the ejecting means to withdraw said restraining means from the chute to pass a 25 type through the chute to a position in front 30 of the ejecting means.

2. In a device of the type described, the combination with a chute for the descent of type therethrough, of means for laterally ejecting type from the chute, a lever, and a 35 pawl carried by said lever for entrance into the chute to restrain the downward movement of the type therein, said lever being synchronized with the movement of the 40 ejecting means to withdraw said pawl from the chute to pass a type to a position in front of the ejecting means.

3. In a device of the type described, the combination with a chute for the descent of type therethrough, of an ejector arm for 45 laterally ejecting type from the chute, a lever means for passing type through the chute to a position in front of the ejector arm, a crank disc for actuating said ejector arm, and a cam on said disc for operating 50 the lever means.

4. In a device of the type described, the combination with a chute for the descent of type therethrough, of an ejector arm for laterally ejecting type from the chute, a 55 lever, a pawl carried by said lever for entrance into the chute to restrain the downward movement of the type therein, a spring connected between the lever and pawl to move the latter toward the type, a crank disc 60 to which said ejector arm is connected, and a cam on said disc for engagement with said lever for the purpose specified.

5. In a device of the type specified, the combination with a chute for the descent of

type therethrough, of means for laterally 65 ejecting type from the chute, and automatic means for forcing a type through the chute into a position in front of the ejecting means.

6. In a device of the type described, the 70 combination with a chute for the descent of type therethrough, of means for laterally ejecting type from the chute, means for passing a type through the chute, and a member below the latter means to force the 75 released type into a position in front of the ejecting means.

7. In a device of the type described, the 80 combination with a chute for the descent of type therethrough, of means for laterally ejecting type from the chute, lever means for passing a type through the chute, and a thrust member carried by said lever means for forcing a released type into a position 85 in front of the ejecting means.

8. In a device of the type described, the 90 combination with a chute for the descent of type therethrough, of means for laterally ejecting type from the chute, lever means for passing a type through the chute, and a pawl pivotally secured to the lever means for forcing a released type into a position 95 in front of the ejecting means.

9. In a device of the type described, the 100 combination with a chute for the descent of type therethrough, of means for laterally ejecting type from the chute, a vertical pawl having a lateral nose portion for engagement with a type to force it downwardly into a position in front of the ejecting means, and a downwardly projecting flange on the pawl below its nose portion to keep the type straight during its downward movement.

10. In a device of the type described, the 105 combination with a chute for the descent of type therethrough, of means for laterally ejecting type from the chute, a vertical pawl for entrance into the chute to force a type downwardly into a position in front of the ejecting means, a horizontal reciprocating member to which said pawl is pivoted for a swinging movement, and an angular projection on said pawl for sliding engagement with the type above to force said pawl out 110 of the chute when it is raised by the reciprocating member.

11. In a device of the type described, the 120 combination with a chute for the descent of type therethrough, of means for laterally ejecting type from the chute, a vertical pawl for entrance into the chute to force a type downwardly into a position in front of the ejecting means, a horizontal reciprocating member to which said pawl is pivoted for a swinging movement, pinching means for holding the type above the pawl stationary, and an angular projection on said pawl for 125

sliding engagement with said type to force said pawl out of the chute when it is raised by the reciprocating member.

12. In a device of the type described, the combination with a chute for the descent of type therethrough, of means for laterally ejecting type from the chute, a vertical pawl for entrance into the chute to force a type downwardly into a position in front of the 5 ejecting means, a horizontal reciprocating member to which said pawl is pivoted for a swinging movement, a pinching slide for holding the type above the pawl stationary, and an angular projection on the pawl for 10 sliding engagement with said type to force said pawl out of the chute when it is raised by the reciprocating member.

13. In a device of the type described, the combination with a chute for the descent of 20 type therethrough, of means for laterally ejecting type from the chute, a vertical pawl for entrance into the chute to force a type downwardly into a position in front of the ejecting means, a horizontal reciprocating member to which said pawl is pivoted for a 25 swinging movement, a pinching slide for holding the type above the pawl stationary, an angular projection on the pawl for sliding engagement with said type to force said 30 pawl out of the chute when it is raised by the reciprocating member, and a rotating means for operating the pinching slide, re-

ciprocating member and ejecting means in synchronism.

14. In a device of the type described, the combination with a chute for the descent of type therethrough, of an arm for laterally ejecting type from said chute, a crank disc for reciprocating said ejector arm, a lever, a pawl carried by said lever for forcing a 35 type into a position in front of said ejector arm, a cam on said crank disc for actuating said lever, a pinch slide for engagement with the type above the nose of said pawl to hold it stationary during the withdrawal of the 40 pawl from the chute, and a cam on said crank disc for actuating said slide.

15. In a device of the type described, the combination with a chute for the descent of type therethrough, of an arm for laterally 50 ejecting type from said chute, a crank disc for reciprocating said ejector arm, a lever, a type restraining pawl carried by said lever, a type thrust pawl also carried by said lever, a pinch slide for engagement with a type 55 above the nose of the thrust pawl pending the withdrawal of said thrust pawl from engagement with said type, and cam means on said crank disc for actuating the lever, pinch slide and ejector lever in synchronism. 60

In testimony whereof I have hereunto set my hand this 18th day of April, 1927.

FRANK H. POEPPELMEIER.
